UNITED STATES PATENT OFFICE.

GEORGE H. RICKE, OF CINCINNATI, OHIO.

SPARK PLUG.

Application filed December 18, 1927. Serial No. 240,589.

The object of my invention is to produce a spark plug for automobile engines which shall be very simple in construction and highly efficient in use, which will not foul by reason of the engine pumping oil or from any other reason.

In carrying out my invention I arrange the electrodes in such position that sediment, oil, carbon, gas and the like from the ignited charge will not reach the points of said electrodes, and thus their points will always be clean, insuring perfect sparking.

Another feature consists in employing an extra electrode which can be used when the electrode in use is burned out or destroyed. It is not in the way and when needed for use it can be bent over to a proper spacing point.

The features and advantages of my invention will readily become apparent from reading the following specification:

In the accompanying drawing forming part of this specification:

Fig. 1, is a view in elevation of my spark plug, showing one side of said plug,

Fig. 2, is a similar view taken at right angles to Fig. 1,

Fig. 3, is a sectional view of the lower end of the plug, to show the relative position of the electrodes and other parts, taken on line 3—3 of Fig. 2, part of the plug being broken away, and

Fig. 4 is a sectional view, taken on the line 4—4 of Fig. 1.

Referring to the drawing, the spark plug itself or body or shell thereof is marked 1, a cylinder skirt is marked 2, provided at its mouth with a baffle disk 3, having arms 4, which join it to the skirt 2. Thus apertures as 5 are formed. By screw threads 6, the

plug is connected in the engine cylinders.

The usual positive electrode 7 is employed and in connection therewith a ground electrode 14 is used, connected to the baffle 3 at 13, so that when the electrode current is applied in connection with the timer, an electric spark is produced between them. In carrying out my invention, I arrange these electrodes or wires differently and to better advantage by positioning them in connection with other parts, so that the spark ends of the electrodes will be above the bottom of the skirt, so that when an explosion takes place, none of the exploding elements or oil will reach the points of said electrodes, and consequently they will always be kept clean and in good working order.

If the electrode 14 should burn out, as sometimes occurs, I provide an auxiliary electrode 15, which is in an abnormal position and when the electrode 14 is destroyed, the electrode 15 can be bent over to the proper sparking position with the electrode 7, thus saving time and money and insuring great convenience.

A spark plug of this character will last longer than the ordinary spark plug and will do better work.

I do not wish to be limited to the exact construction herein shown as the same may be modified to some extent and I claim any modifications which will fall within the scope of this specification and claims.

What I claim as new and my invention and desire to secure by Letters Patent is:

1. A spark plug including a shell having external threads to engage the threads of an engine cylinder, a skirt united with the shell and projecting downwardly from the lower edge of the same, arms projecting downwardly from the lower edge of the skirt, an imperforate disk-shaped baffle connected to the lower ends of the arms and spaced from the lower edge of the skirt, a central electrode extending into the shell and skirt, insulated from the shell and skirt, and having its lower end terminating within the skirt, but in close proximity to the lower edge of the latter, and a second electrode connected to the disk and projecting upwardly into the skirt and terminating in close proximity to the lower end of the central electrode, the opening between the baffle and the lower edge of the skirt permitting access to the points of the electrodes for cleaning purposes.

2. A spark plug, including a metallic shell having a depending skirt, arms depending from the skirt, an imperforate disk-shaped baffle carried by the arms in spaced relation to the lower edge of the skirt, a central electrode extending into the skirt and terminating within the latter, and a pair of malleable electrodes attached to said disk-shaped baffle and projecting upwardly and terminating within the skirt, one of said malleable electrodes having its upper end arranged in close proximity to the lower end of the central electrode.

3. A spark plug, including a metallic shell having external threads adapted to engage the threads of a spark plug aperture of an engine cylinder, a cylindrical metallic

skirt integral with the shell and depending from the latter, metallic arms depending from the skirt and merging into the lower edge of the latter, a metallic disk-shaped baffle of substantially the same diameter as the external diameter of the skirt, integral with said arms, the baffle being spaced from the lower edge of the disk to provide an opening, a central electrode extending into the shell and skirt, and having its lower end terminating within the skirt, and a pair of electrodes projecting upwardly from the

baffle and terminating within the skirt, one electrode of the pair having its upper end arranged in close proximity to the lower end of the central electrode, and the other electrode of the pair being formed of malleable material to permit the same to be bent toward and away from said central electrode. 15

In testimony whereof, I affix my signature 20 at the city of Cincinnati, county of Hamilton, and State of Ohio, this 15th day of December, 1927.

GEORGE H. RICKE.
